Patented July 9, 1912.

UNITED STATES PATENT OFFICE.

ELMER E. WOODWORTH, OF RICHMOND, VIRGINIA.

CURTAIN-FIXTURE.

1,081,898.

Specification of Letters Patent.

Patented July 9, 1912.

Application filed January 24, 1912. Serial No. 673,100.

To all whom it may concern:

Be it known that I, ELMER E. WOODWORTH, a citizen of the United States, residing at Richmond, in the county of Henrico 5 and State of Virginia, have invented certain new and useful Improvements in Curtain-Fixtures; and I do hereby declare the following to be a full, clear, and exact description of the invention, such as will enable others skilled in the art to which it 10 pertains to make and use the same, reference being had to the accompanying drawings, and to the letters and figures of reference marked thereon, which form a part of this 15 specification.

This invention relates to new and useful improvements in adjustable brackets for supporting curtain shade poles and comprises a simple and efficient device of this 20 nature, having various details of construction and combinations and arrangements of parts which will be hereinafter fully described, shown in the accompanying drawings and then specifically defined in the appended claim.

I illustrate my invention in the accompanying drawings, in which:—

Figure 1 is a perspective view showing the application of my invention to the 30 frame of a window. Fig. 2 is a sectional view longitudinally through the adjustable bracket, and Figs. 3 and 4 are detail views of the two bracket sections.

Reference now being had to the details of 35 the drawings by letter, A designates one of the bracket members and B the other, each of which is provided with an angled end with spurs D projecting therefrom. Said bracket member A has a bracket arm A' 40 projecting therfrom, having apertures E therein for the reception of the spindle ends of shade rollers, and also lugs F which are apertured for the reception of the pins H of the dog I, which has a contracted end I'.

45 The bracket member B has a series of slots

B' formed parallel to each other and spaced apart as shown, and each slot is adapted to receive the contracted end of the dog I to hold the brackets in adjusted positions.

In adjusting the bracket plates, the spurs 50 upon the upper plate are pushed down into the top of the casing, the contracted end of the dog inserted in one of the slots in the plate B and the spurs in the lower plate brought into contact with the under edge of 55 the casing, after which a swinging movement of the lever I, the pintles of which are journaled in the ears F, will cause the lower plate to be raised and its spurs will be drawn up into the lower edge of the casing. 60 By reason of the peculiar shape of the dog, when the same is in the position shown in Figs. 1 and 2, with the inwardly bent portion directly underneath the pintles it will 65 serve to hold the plates in locked position, it being understood that the weight of the shade roll will be supported by the plate A.

What I claim to be new is:—

An adjustable curtain pole supporting device comprising two bracket plates having 70 spurred ends for engagement with the upper and lower edge of a casing of a window frame, one of said plates having a series of transverse slots therein, bracket arms projecting from the opposite edges of the other 75 plate, a dog having pintles pivotally mounted in said bracket arms, one end of the dog being contracted and adapted to engage one of said slots and its shank portion with an inwardly bent portion adapted to contact 80 with the face of the slotted plate at a location substantially underneath the pivotal points of the dog, as set forth.

In testimony whereof I hereunto affix my signature in the presence of two witnesses. 85

ELMER E. WOODWORTH.
